UNITED STATES PATENT OFFICE.

JAMES R. MACCOLL, OF PAWTUCKET, RHODE ISLAND.

DESIGN FOR A WOVEN FABRIC.

SPECIFICATION forming part of Design No. 16,761, dated June 29, 1886.

Application filed January 7, 1886. Serial No. 187,923. Term of patent 7 years.

To all whom it may concern:

Be it known that I, JAMES R. MACCOLL, of Pawtucket, in the county of Providence and State of Rhode Island, have invented and produced a new and original Design for Woven Fabrics, of which the following is a full, clear, and exact description.

Reference is to be had to the accompanying drawing, forming a part of this specification, and which illustrates my design.

The leading feature of my design consists in a textile fabric ornamented by a series of squares bounded on all sides by strands which cross each other at the corners of the squares, and are interrupted or partially concealed at the central parts of the sides of the squares.

These strands spread apart at their intersecting points and contract at the said concealed or interrupted points.

I claim--

The design for textile fabrics herein shown and described, the same consisting in the fabric ornamented by a series of squares bounded on all sides by strands which cross each other at the corners of the squares, the said strands separating or spreading apart at their points of intersection and contracting between said intersecting points.

JAMES R. MACCOLL.
